Patented Dec. 31, 1957

181,805

TEA TABLE

Arthur G. Morris, Shepherd, Mich.

Application December 14, 1956, Serial No. 44,199

Term of patent 14 years

(Cl. D33—14)

FIG. 1.

FIG. 2.

FIG. 3.

Figure 1 is a perspective view of a tea table embodying my new design with portions of the top being broken away for convenience of illustration;

I claim:

The ornamental design for a tea table, as shown and described.
